MAYER, LTD.(57) **CLAIM**

The ornamental design for a dissolved oxygen sensor, as shown and described.

DESCRIPTION

FIG. 1 is a top, front perspective view of a dissolved oxygen sensor;

FIG. 2 is a top, back, perspective view thereof;

FIG. 3 is a front, bottom perspective view thereof;

FIG. 4 is a bottom, back perspective view thereof;

FIG. 5 is a bottom view thereof;

FIG. 6 is a top view thereof;

FIG. 7 is a right side view thereof;

FIG. 8 is a back view thereof;

FIG. 9 is a front view thereof; and,

FIG. 10 is a left view thereof.
